DESOLDERING TOOL OR THE LIKE William S. Fortune, 14250 Dearborn St.,
Panorama City, Calif. 91402

Filed Nov. 1, 1968, Ser. No. 14,279

Term of patent 14 years

Int. Cl. D8—02

U.S. Cl. D8—30

FIGURE 1 is a plan view of an example of a desoldering tool or the like embodying the claimed design;

FIGURE 2 is a bottom view thereof;

FIGURE 3 is a left side elevational view thereof, the right side elevational features of the claimed design being substantially a mirror image of those shown in this figure; and

FIGURE 4 is a frontal, end elevational view thereof.

Portions of FIGS. 1, 2 and 3 have been broken away for convenience of illustration.

I claim:

The ornamental design for a desoldering tool or the like, substantially as shown and described.
